Primary Examiner — Christian P. McLean*Assistant Examiner* — Jasmine L. Comedy(57) **CLAIM**

The ornamental design for a support base as shown and described.

DESCRIPTION

- 1.1 : Perspective
- 1.2 : Perspective
- 1.3 : Front
- 1.4 : Back
- 1.5 : Right
- 1.6 : Left
- 1.7 : Top
- 1.8 : Bottom

(Continued)

The characteristic features of the design are the shape and relative orientation of the support legs. The broken lines depict portions of the support base that form no part of the claimed design.

1 Claim, 8 Drawing Sheets
